BUFFET CHAFER

Carl H. Rickmeier, Jr., Sheboygan, Wis., assignor to The Vollrath Co., Sheboygan, Wis., a corporation of Wisconsin

Filed Aug. 12, 1968, Ser. No. 13,112

Term of patent 14 years

Int. Cl. D7—04

U.S. Cl. D44—15

Fig. 1

Fig. 2

FIG. 1 is a perspective view of a buffet chafer showing my new design, with the burners in extended position; and FIG. 2 is a rear elevational view.

I claim:

The ornamental design for a buffet chafer, as shown.
